PIN-UP BOARD

Marguerite G. Brooks, Darien, Conn.

Application May 24, 1954, Serial No. 431,650

4 Claims. (Cl. 28—15)

This invention relates to a pin-up board, and has for an object to provide an improved device of this character for holding a pattern and pins associated therewith for outlining the design of the pattern, for use with a plurality of spindles or bobbins carrying threads or narrow ribbons to be interwoven with filling threads by a shuttle or similar device in making lace, fabrics or similar articles.

Another object is to provide a device of this character in the form of a board, comprising a lower board portion having an open outlined space on the top thereof, in which are arranged side by side a plurality of rectangular blocks or sections, to which the pattern and the design outlined by the pins may be held during the weaving or fabricating operations, and whereby during these operations after a portion of the design has been fabricated the blocks may be shifted to different relative positions, if desired, to more favorably position the pattern or design for continuing further operations, without requiring that the pins outlining the design be removed or shifted with respect to their supporting block or blocks.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In this drawing:

Fig. 1 is a top plan view of a board constructed according to this invention, showing the initial operations of weaving or fabricating a design thereon;

Fig. 2 is a partial side elevation and partial vertical section;

Fig. 3 is a view similar to Fig. 1 showing how the pattern and design being fabricated may be shifted or rearranged after partial completion thereof to facilitate fabrication of further portions of the design, and

Fig. 4 is a perspective view of one of the plurality of supporting and positioning blocks or sections for the pattern and design.

This board is designed to be used in connection with a series of spindles or bobbins and shuttles for making yardage, place-mats and so forth, and can be used not only for making lace, but can be used for making woven fabrics as well. It can also be used as a blocking board for sweaters, as well as a sewing board for use by pinning things to it and laying them out; securing one end of a hem so the operator can hem more quickly, or baste more quickly, and the like.

The preferred construction shown comprises a base portion 10, preferably of substantially square or other rectangular shape, and this may be a one-piece board of any desired size or thickness. For the usual operations it is preferably about twenty inches long and eighteen inches wide, although of course, as indicated, it may be of other sizes if desired. Along each of the opposite side edges and on top of the base portion are secured

2

elongated sections 11 which may be permanently secured to the top of the board, but are preferably hinged to it as indicated at 12 so that these sections may be swung outwardly away from the top of the lower portion to clear the top of this lower portion. There is a similar elongated section 13 secured along the lower edge of the lower portion, and this is preferably permanently secured to this lower portion, although it could be hinged the same as the side sections 11 if desired. Sections 11 and 13 form three sides of a rectangular open space on the top of the lower portion 10 in which are mounted side by side a plurality of blocks 14 which are preferably of square or rectangular shape, which fill this space between the members 11 and 13 and are unattached or free from the lower portion 10 so that they may be shifted to different relative positions on the top of the member 10 and held by the side members 11 and 13. To facilitate description of the use of this board these blocks are numbered 1 to 9 inclusive.

20 The different members of this board may be made of different materials, but a very satisfactory material has been found to be insulating wallboard or fiber board, of about three-eighths inch thickness, as this has the required stiffness or rigidity, is light weight and readily receives the pins used in securing and outlining the pattern during the weaving or fabricating operation, and holds the pins firmly during this operation. It is preferred to make both the lower portion 10 and the blocks 14 of this material so that should, in securing the pattern or outlining the design, a pin happen to come at the crack or dividing line between adjacent blocks, it would pass down into the lower portion 10 and be held the same as it would if inserted in the upper thickness comprising the blocks. It is also preferred to cover the top surfaces of the blocks with a finishing material 15, such, for example, as felt or woven fabric, secured thereto by gluing, cementing or similar means.

As illustrating the use of this board, a pattern 16 is shown having outlined thereon a design 17 for any suitable article, as, for example, a lace collar. The design illustrated comprises a curved central portion 18 indicated by the cross lines, between two lines of pin pricks 19 and 20, and end portions 21 indicated by lines at substantially right angles to the adjacent portions of the lines 18 and outlined by the pin-pricks 22 and 23. This pattern and design is shown as laid on the upper series of blocks 14 and may be secured to any of the blocks shown, but preferably for fabricating or weaving the first portion of the design comprising the portion 21 at one end of this design the pattern is preferably secured to blocks in the upper row, but in the present case, because this would carry the design above the board into the space required for the heading, it is shown as secured over the central block 5 of the second or middle row of the blocks, and the pins 24 outlining this portion of the design are inserted through the pin-pricks 22 and 23 and along their inner edge 25. The pins along this edge 25 are also used to secure the ends of a series of threads or narrow ribbons 26 wound on a series of spindles or bobbins 27, and with this arrangement the narrow ribbons on these spindles or bobbins all depend from these pins in substantially parallel relation, and if the board is held tipped or inclined with the upper edge raised somewhat above the lower edge the spindles will hold the threads or ribbons substantially parallel and with uniform tension. Then while these threads or ribbons are so held the filling thread 28 may be interwoven with these ribbons by means of a shuttle 29 on which this thread is wound, and passing it across and between the various ribbons 26 to fill out the design as indicated on the pattern 16.

After the end portion 21 of the design is completed and it will be necessary to shift the bobbins or spindles to the

left for starting the body portion 18 of the design, the operator may shift one or more of the blocks 14 to so shift the pattern and the design that the bobbins or spindles 27 and the ribbons 26 leading therefrom will be most effectively arranged for continuing the weaving or fabricating operation, and still have the ribbons and the bobbins depending in an upright position from the pins outlining the design. In the arrangement illustrated as an example, this is done by shifting the block 5 on which the pattern is held by the pins 24 into the upper row of blocks in the position formerly occupied by the block 2, and the block 5 has also been turned to the left through ninety degrees, as shown in Fig. 3, so that the ribbons will depend from the pins 30 at the line 23 between the end and body portions of the design, in an upright position the same as shown in Fig. 1, for weaving the end portion 21 of the design. This shifting and rearranging of the blocks to rearrange the pattern and design being woven for most effective operation and to facilitate these operations may be carried out throughout the weaving of the entire design. It will be seen that this will permit the most effective positioning and arrangement of the pattern and design to facilitate the weaving operation, or that is, permit shifting and repositioning of the pattern and design for most effective operation on any given part thereof, without requiring the removal of any of the pins and repositioning of the pattern or design on any given block, as the blocks themselves may be repositioned and rearranged to secure this effect, and this may be done throughout the weaving or fabrication of the entire design.

It will be understood that although in the example shown the pattern or design has been pinned to one block only, it may be pinned to two or more blocks or sections if found desirable, according to the width of the article being made. When the work has progressed to a given point the sections on which the pattern or design is fastened may be lifted or shifted to a different location as found desirable, and the other sections or blocks rearranged accordingly for the most effective positioning of the pattern and design for the operations involved. This rotation of the blocks or sections as the work progresses makes it unnecessary to remove the pins from the finished material and move it up on the board, as would be necessary when weaving on one flat surface. The lower section, or row of blocks 7, 8 and 9, would be used in case a wider fabric is to be woven, with the board turned sideways, or in case sections 1 to 6 must be more centrally placed.

Having thus set forth the nature of my invention, I claim:

1. A pin-up board of the character described comprising a base portion and an upper portion on top of the base portion, said upper portion comprising elongated sections secured to the base portion at its opposite side and lower edges forming a central open rectangular space, a series of rectangular blocks on the base portion side by side in said open space and unattached to the base so they may be shifted to different relative positions in said space, and said blocks being of a material adapted for ready insertion of pins to facilitate pinning a pattern to the upper surface thereof.

2. A pin-up board of the character described comprising a base portion, elongated sections secured on top of said base portion and extending along its opposite side and lower edges forming a central rectangular open space at the top side of the base portion, a series of rectangular blocks arranged side by side in and filling said open space and unattached to the base portion so they are shiftable to different relative positions in said space, and said blocks being of a fibrous material adapted for ready insertion of pins indicating a pattern for lace or similar article.

3. A pin-up board of the character described comprising a base portion, an elongated section secured thereon along its lower edge and elongated side portions hinged to the base portion along its opposite side edges, said elongated portions forming sides of an open rectangular space on the top side of the base portion, a plurality of rectangular blocks arranged side by side in said space and free from the base portion so as to be shiftable to different relative positions in said space, and said blocks being of material adapted for ready insertion and holding of pins indicating a pattern for lace or similar article.

4. A pin-up board of the character described comprising a base portion of fiber board, elongated sections secured thereto along its opposite side and bottom portions forming sides of an open rectangular space at the top side of the base portion, and a plurality of rectangular fiber board blocks arranged side by side in said space and free from the base portion so as to be shiftable to different relative positions in said space for different arrangements of a pattern pinned to one or more of the blocks.
